FOUNDATION AND THE LIKE.

Application filed August 5, 1925. Serial No. 48,193.

My invention provides a method of treating or manipulating certain soils to increase their load-carrying capacity or strength. The soil or earth thus treated may be used 5 as a building foundation carrying heavy downward pressures, or as floor slabs and walls for coffer dams and similar excavations or as a consolidated mass through which tunnels can be driven or in various 10 other analogous ways.

The ordinary supersaturated or highly watered natural deposit (wet earth or mud) offers very little resistance to stresses imposed upon it tending to change its shape 15 or to displace it laterally and upward. I propose to change such wet earth into a shale-like material practically impervious to water and capable of resisting tension as well as compression, and greatly improved 20 in resistance to change of volume or shape and to lateral displacement.

I first provide vertical drains fairly close together depending on the special character 25 of the material. I also exert lateral compression on the mass of earth surrounding the drains. The pressure may be applied by the drains themselves during their construction; or it may be applied by driving solid 30 wooden or concrete piles, by stock-ramming, and in similar ways referred to hereinafter in detail. Or the lateral pressure may be applied in several different ways on the same job. The process is intended for soils 35 which cannot be dewatered merely by gravity or ordinary drainage, and in which a considerable pressure externally applied is necessary to squeeze out the water to the desired extent. This is what happens in such soils when a building erected thereon settles. The soil is compacted by the expulsion 40 of the water laterally (in which term we include upwardly). The resistance of the water to expulsion is so great that the building settles slowly. Sometimes it takes 45 several years to reach a condition of equilibrium where the resistance of the remaining water to separation from the earth particles is equal to the load, and settling stops. Such settlement, being generally only a few 50 inches, does not involve the application of an extraordinary amount of work, measured in foot pounds. For any ordinary case we

can by the present invention eliminate the water beforehand and in a comparatively brief period,—bringing the soil to the condition corresponding to that occurring after a year or two of service in support of a building. This prompt dewatering is due to the fact that the pressure can be far more 55 widely distributed throughout the area and depth of the stratum and at a higher pressure by the devices which I employ, than it can be by the building itself and that the distance that the water must travel in the material is reduced. 60

The accompanying drawings illustrate 65 embodiments of my invention.

Fig. 1 is a plan showing an arrangement of drains and pressure devices over a given 70 area;

Fig. 2 is a vertical sectional view showing the pressure-producing devices and the drains passing up through a mat of concrete;

Fig. 3 is a sectional view of a device for 75 ramming sand in piles;

Figs. 4 and 5 are respectively a half-plan and section of a cofferdam; and

Fig. 6 is a vertical cross-section of a tunnel.

The drawings are chiefly diagrammatic, 80 to illustrate the method, the details of the apparatus and structures involved being capable of wide variation.

For example, a very great number of ways may be utilized to exert lateral pressure in the soil and to the required depth. I have illustrated in Fig. 3 a sand-ramming pile but I may use expanding mandrels, liquid or gas pressure devices, solid wooden or concrete piles or devices for ramming in 85 pervious or impervious material, such as sand or a concrete mixture. The stock-ramming may extend the full depth of the pipe or be limited to a desired level. 90

The pressure-producing means may be 95 used as elements of construction, as in tunnels or coffer dams, or as piles in foundations. The provision of drains facilitates the driving of ordinary wooden or concrete “point-bearing” piles by reducing the resistance to driving and the danger of uplift 100 and lateral movement of the piles and of the mass.

Referring now particularly to Fig. 3, a

pipe 1 with a detachable point 2 at its lower end is driven to the required depth, and its lower end filled with sand 3 introduced through a pipe 4. An annular ram 5 is 5 lifted and dropped on the sand, which drives the point 2 of the pile down and drives the sand out laterally against the surrounding earth as indicated. The quantity of sand and the extent of the hammering operation 10 will determine roughly the diameter of the resulting column of sand; the column being extended upward by continuing the supply of sand as the casing 1 is lifted. Such an operation produces a vertical drain and at 15 the same time compresses the earth surrounding the drain so as to force out of it a quantity of water greatly in excess of that which would flow out by gravity alone.

In many situations the top soil is not 20 suitable as a working platform, as men, horses or plant in motion convert the top surface into a sea of mud. I have in such cases laid a floor of concrete to provide a working platform on which the superstructure was started, comprising first the footings or mat used in distributing the load of 25 columns or walls.

In my method, using stock ramming or 30 liquid or gas pressure to produce lateral pressure in the mass, the intensity of lateral pressure used near the upper surface of the mass is limited, as lateral pressure will produce lateral and upward motion more easily near the surface than at depths, and 35 liquid or gaseous pressure would blow out.

I, therefore, in such cases, may construct 40 a mat of concrete over the entire area of support, arranging at the proper points to have vertical cylindrical openings, properly spaced to coincide with the location of the vertical drains and the pressure-producing piles.

The vertical drains may be constructed 45 before the mat, or afterward, but in any case each vertical drain should have a free outlet through the mat.

The pressure-producing piles should be 50 constructed after the mat has set a reasonable time. The pipe pile or expanding mandrel may be driven through the hole provided for it. The stock ramming can be performed in the ordinary manner, but with better results, especially near the upper end.

If compressed air or water pressure is 55 used to expand the vertical hole in the mass, then the hole through the mat may be lined with a steel pipe, concreted or grouted so as to be air tight and water tight, and with top 60 connections for the water or gas pressure conveying pipe.

The mat will serve as a pressure retaining cap to the air or water used and will 65 also act as a load to prevent the mass rising locally near to the pipe, as a result of lateral pressure.

After the mass is compressed the hole may be concreted.

At any time grout under pressure may be used under the mat.

For a better understanding of the invention, I will describe the application of it to a specific example. A structure was set 70 on a reinforced concrete base or slab 5 feet thick and about 80 feet wide by 110 feet long, an area of 8,800 feet. The slab was 75 placed on natural material, the under side of the slab being placed about 10 feet below the surface of the ground.

Below the slab, the natural material was, 80 for a depth of 15 feet, a dry sandy clay soil, through which ran small openings like worm holes. These holes above water level were filled with air. At a depth of 50 feet below the slab rock was encountered, practically level. Above the rock, and below 85 the dry soil, the material was wet and would normally be described as a wet clay.

After completion of the structure the total load on the mat was 26,400,000 pounds; under 90 which the mat settled 2 inches. When the building was loaded, in ninety days the total load was doubled and in this period there was a settlement of 2 feet. There was no apparent movement of the top surface 95 of the adjacent unloaded areas, but water appeared as springs flowing through the concrete slabs and even in places through pervious joints in the concrete walls resting on the slab although the water level in the soil, except at the site of the silo, had not 100 changed and was 15 feet below the level at which water appeared in the slab. It was evident that the only source of water was from the saturated clay bed, 15 feet below the slab. The settlement was principally 105 the result of the consolidation of the super-saturated clay bed.

The work or energy involved in the settlement was approximately 52,800,000 foot 110 pounds or 26 horse power for one hour. The displacement of the mat in moving 2 feet was $(8,800 \times 2)$ 19,600 cubic feet. This volumetric change in the soil was chiefly 115 in the upper 40 feet; the lower 10 feet immediately above the rock contained solid rock fragments and dense blue clay.

To produce the same effect before erecting the building we must artificially displace 2 cubic feet per square foot of area. Or an additional 2 cubic feet of new material must be introduced for each square foot of surface and 40 feet of depth. This is a five per cent consolidation. In such a case I would drive sand-piles serving as drains on 10 feet centers, arranged in squares, or better staggered so as to have one preliminary drain pile to every 100 square feet of area. This preliminary pile may have a cross-section of 1 square foot.

I would drive approximately 130 of these 120

preliminary drains spaced over an area $90 \times 120'$.

I would then drive approximately 390 pressure-exerting piles, interspaced equally between each of the preliminary piles. Each of this second group of piles would have a cross-section finished of $1\frac{1}{2}$ cubic feet per foot of height.

For each 100 square foot area there would 10 be introduced into the soil

1 pile 1 sq. ft.	Section $\times 40' = 40$ cu. ft.	
3 pile $1\frac{1}{2}$ sq. ft.	Section $\times 40' = 180$ cu. ft.	
Total.....		220 cu. ft.

This total displacement is slightly in excess 15 of the theoretical requirements.

Fig. 1 illustrates the arrangement described, the drains being indicated at 6 and the pressure-producing piles at 7.

If these piles were made of concrete the 20 cost of material and mixing would be about \$8,000, compared with a cost of about \$1,000, if they were of sand.

More important than the above saving is the fact that in the material described it 25 would be impractical to drive the concrete piles to the depth required. The first piles would compress the mass, without affording any opportunity for the water to escape and it would be impossible to drive additional 30 piles, except after allowing an unreasonable time for the water to escape, (no draining system having been established) unless the material was displaced laterally or upward, which would result in reducing the value 35 of the piles already driven.

Using my method, the load of the structure would be distributed over the consolidated mass by a distributing mat 8 or footings. The mat would then rest on a consolidated mass comprising vertical columns of 40 consolidated sand spaced uniformly in the mass of consolidated and partially dewatered granular material. Both the sand and the original, but dewatered mass are capable of 45 supporting the unit-load which the structure will place on the mat.

If wooden or concrete pressure-producing piles are used, the safe load on such piles 50 will be greatly increased by the change in character of the surrounding material due to prompt drainage and moreover a less number of piles will suffice because the material between the piles can be safely counted on to carry a part or all of the load.

By my invention, silty material such as 55 that forming the bed of some harbors can be converted into a reliable, water tight, pressure-resisting material capable of acting as a cofferdam wall.

Where the material in place does not reach 60 the water surface it will be necessary to build an upward extension between the top of the consolidated natural material and the water surface. Where the material, as in marshes, 65 swamps, etc., extends up to or above water

level, the wall formed by my invention will alone be sufficient. In the latter case I will proceed substantially as follows:

I will first determine the shape and dimensions of the excavation to be made and the 70 general character of the material below the bottom of the excavation. If the excavation requires protection against the bottom lifting, as well as against lateral motion, I will create a bottom and walls of consolidated 75 material by means herein described. If the excavation requires protection against lateral motion only, I will create only walls of consolidated material.

In constructing the bottom (if required) 80 I will drive pipe piles to a sufficient depth below the proposed excavation depth to give a floor slab of consolidated material of ample thickness to resist uplift, when the excavation, or a predetermined section of the ex- 85 cavation, is made.

I will consolidate this section by constructing first a series of vertical drains extending to the surface, and secondly by interposing 90 piles designed to produce lateral pressure. 95 When the pressure-producing effect has progressed upward from the point of the pile to the excavation level I will, in general, discontinue the operation, leaving the mass above the protective floor in natural condition. To produce the wall I will, exterior to 100 and enclosing laterally the proposed excavation, drive one, two or more lines of vertical drains and one, two or more lines of pressure-producing piles, to the proper depth and width so that the consolidated material thereby produced will connect with the floor (if floor be needed) or with an impervious and compact substratum, or if there be neither floor nor impervious substratum, 105 then to such depth as may be necessary to provide a solid foundation for the wall below the level of the excavation to be made.

I may construct a single closed wall; in 110 plan having the form of a circle, ellipse, square or polygon, enclosing the entire excavation, or in certain cases I may prefer to consolidate the enclosed area as well as the required walls, or to consolidate a part of 115 the enclosed area, so as to sub-divide the operation, or, in general, I may consolidate such parts or portions of the mass as to facilitate the work to be performed.

An example is shown in Figs. 5 and 6. 120 The level of a piece of marshy ground is indicated at 9 in which it is desired to make a circular excavation 10, of which the floor and side walls are to be consolidated. Drains 11 are first opened from the top of the marsh to the level 12 to which the consolidation is to be carried, and pressure piles 13 are driven as explained above to compact the earth laterally. The stock-ramming of the pressure piles is carried from the level 12 only to the level of the bottom 14 of the 125 130

intended excavation. Around the excavation are driven drainage piles 15 and pressure piles 16, the stock-ramming of the latter being carried clear up to the surface 9. 5 Thereafter the excavation is made and the floor and wall thereof (extending roughly to the line 17) will have been strengthened sufficiently to hold their shape and to serve as a coffer dam to hold back water from 10 the excavation.

In constructing tunnels, I drive two lines of vertical drains paralleling the axis of the tunnel but outside of the lines of side excavation. I then consolidate the mass between 15 the lateral lines of drains by pressure-producing piles. In constructing the pressure-producing piles, I use a granular material impervious to water when producing lateral pressure at the levels of the invert and roof, 20 so as to avoid leaks when excavating the tunnel section.

In order to supply temporary support to the roof while excavating I may use concrete or wooden piles as pressure-producing 25 piles, so as to form a concrete or timber supporting element extending between the consolidated mass forming the roof and the consolidated mass forming the floor of the excavation to be made.

30 These concrete or timber columns will serve as temporary support for the roof during the excavation of the tunnel and can be removed when or after the permanent lining is in place.

35 An example is shown in vertical cross-section in Fig. 6. The surface of the earth is indicated at 18. Along the desired line are sunk drainage piles 19 and pressure piles 20. In the latter impervious material 40 is used outside of the line of excavation 21, up to the top line 22 of the intended consolidation and down to the bottom level 23 thereof. The piles 24 are pressure piles, using concrete between the levels 25 and 45 26 shortly above and below the tunnel cross-section. A lining subsequently built in the tunnel is shown at 27. The drains and pressure-producing piles consolidate the earth between the levels 22 and 23 and the planes 50 28 and 29 at opposite sides. The earth in this cross-section is strengthened so as to hold its shape and facilitate the excavating and lining of the tunnel.

55 The depth to which the consolidation is carried will depend on the character of the material and the intended load, both of which can be determined beforehand, the depth being to rock or hardpan or to any 60 material encountered which is sufficiently compact in its natural state to support the load imposed on it without undue volume change. The drains are referred to as vertical, by which I mean that they shall have at least a vertical component though they 65 may be oblique as, for example, in draining

a mass of conical form. The drains should be pressure-resisting so as to remain open during the compacting of the surrounding material. They may be made of a great variety of materials which are pervious to 70 water; such as unglazed terra cotta, porous tubes of concrete or mortar, sand, slag, gravel or other granular material permitting a free passage of water. In some materials a hole may be bored with an ordinary post 75 hole auger and filled with material which permits a flow of water but holds back the solid material of the surrounding mass. The granular material may be tamped in order to completely fill the hole and to compress 80 the surrounding mass. In other materials it is not practicable to maintain an open hole, and methods involving the sinking of hollow piles must be resorted to. An example of such a method has been described 85 in connection with Fig. 3 above. And there are many other ways of achieving the same purpose.

The drainage "piles," as I call them, may be applied in such a way as to also produce lateral compression, and my invention may be practiced with such piles alone properly distributed according to the nature of the earth and the intended loading. Or, as first described, such drainage piles may be supplemented by others generally of a simpler character and designed solely or chiefly for producing lateral compression.

The chief advantage of the invention arises from the use of vertical drains, whereby the frictional resistance to be overcome in the dewatering of the mass is reduced and the time required for dewatering is shortened according to the extent of subdivision of the mass by the drainage and pressure piles. Thus the mass can be cheaply and rapidly dewatered and compressed beforehand, to the same or a greater extent which has been common in the settlement of foundations and loaded buildings acting over a 100 longer period of time.

Various modifications of the process and details described may be made by those skilled in the art without departing from the invention as defined in the following 105 claims.

What I claim is:—

1. The method of strengthening a body of earth which consists in forming drains at numerous points in the area of the mass and compacting the material laterally also at numerous points to force the water out of it by way of such drains.

2. The method of preparing a body of earth to serve as a foundation for a structure which consists in determining beforehand the extent to which it would be compacted by the weight of the structure and dewatering and compacting the earth to substantially the determined extent by forming 110

vertical drains therein and applying lateral pressure to the mass.

3. The method of claim 1, first laying a mat on the earth and then draining and compacting the earth beneath the mat.

4. The method of claim 1, compacting the material by driving pressure-producing piles about the drains.

5. The combination in a body of earth of pressure-resisting vertical drains for 10 water and means for exerting lateral pressure on the earth surrounding said drains.

In witness whereof, I have hereunto signed my name.

DANIEL E. MORAN.
